UNITED STATES PATENT OFFICE.

ALBERT J. RAU, OF CLIFTON, NEW JERSEY.

DYEING PROCESS.

1,131,083.

Specification of Letters Patent.

Patented Mar. 9, 1915.

Application filed March 4, 1914. Serial No. 822,315.

To all whom it may concern:

Be it known that I, ALBERT J. RAU, a citizen of the United States, residing at Clifton, New Jersey, have invented certain new and useful Improvements in Dyeing Processes, of which the following is a clear, full, and exact description.

This invention relates to dyeing processes and particularly to such processes as are 10 used for dyeing fabrics.

A principal object of the invention is to provide a simple process which will insure a uniform dyeing effect throughout the entire length of the material dyed.

15 A further object of the invention is to effect the dyeing in such a way that the dye liquor of the bath comes directly in contact with the surface of the fabric, first on one side and then on the other, so that the dye liquor is forced through the fabric, first in 20 one direction and then in the other.

Further objects of the invention will appear more fully hereinafter.

The drawing illustrates apparatus which 25 may be used in carrying out my process.

Figure 1 is a longitudinal vertical section; Fig. 2 is a transverse vertical section through the apparatus shown in Fig. 1; Fig. 3 is a detail of a portion of a drum 30 constituting a feature of the apparatus; Fig. 4 is a detail showing a portion of the rim of the drum; Figs. 3 and 4 are upon an enlarged scale.

The apparatus by means of which my 35 process is most conveniently carried out preferably comprises a vat 1 having end walls or heads 2 between which I prefer to mount two rotatable drums 3 and 4. These drums are preferably constructed on a plurality of spiders 5 having hubs 6 by means of which they are attached rigidly to the shafts 7. The ends of the drums are open and the length of the drums is such that each drum substantially bridges the distance 40 between the heads 2; in this way the extremities of the drum substantially close off communication between the space around the drums and the interior of the drums adjacent the heads. The heads 2 are preferably provided with openings 8 of segmental 45 form, and the vat is formed with false heads 9 which are inclosed so that conduits 10 are formed at each end of the vat communicating with the interior of the drums 50 through the openings 8. In the lower part of the heads 2, openings 11 are formed in which are mounted impellers 12 attached to

a common shaft 13 which is arranged to be rotated from the exterior by any suitable means such as belt pulley 14.

60 The outer surface of each drum is preferably built up by attaching longitudinal bars or rods 15 on the rims of the spiders in some such manner as indicated in Figs. 3 and 4. On these rods 15 I wrap helically about the 65 drum a continuous fine wire 16 and then on this wire I lay an envelop or inner covering 17 of coarse mesh wire gauze. Over this I place an outer cover 18 of fine mesh gauze wire. The shafts 7 are preferably provided 70 with belt pulleys 19 and 20 respectively which are connected by a horizontal belt 21 so that when pulley 20 is rotated by a driving belt 22, pulley 19 will also be rotated. Adjacent each pulley a clutch 23 is provided 75 corresponding to each drum. When one of the clutches 23 is thrown in, its corresponding pulley will be rotated so as to rotate its corresponding drum.

In carrying out the process, the fabric 80 to be dyed is wrapped in a coil 24 upon one of the drums. This may be accomplished while unwrapping it from a roller 25 supported on bearings 26 on the vat. As illustrated, this coil is formed on the right hand drum in Fig. 2. The clutch of the right hand drum is then thrown open and the corresponding clutch of the left hand drum is closed. The end of the web is then attached in any suitable manner such as by 90 pinning it to the surface of the left hand drum and the belt 22 is then driven so as to rotate the left hand drum in the direction of the arrow. This winds the web from the right hand drum to the left hand drum so 95 that the layers of the web on the right hand drum pass over and form a coil of layers on the left hand drum. While this is taking place, the shaft 13 is rotated so that the impellers 12 which are of opposite pitch draw 100 the dye liquor from the ducts 10 into the space 27 under and surrounding the drum. This produces a circulation in the direction indicated by the arrows, and produces an 105 excess of hydrostatic pressure on the outer sides of the drums which forces the dye liquor through the layers of the fabric into the interior of the drums. After the web has completely passed from one drum to the other, it is passed back again in the same 110 manner, the direction of rotation of the shaft 13 being the same as before so that the direction of the circulation of the dye liquor is the same as before. In this way it

will be seen that the entire length of the web on one side is subjected to direct contact with the bath under hydrostatic pressure, forcing the dye liquor through the fabric from that side. On account of the fact that the web is wrapped in opposite directions on the two drums, it will be seen that the entire length of both sides of the cloth will be brought directly in contact with the bath and subjected to hydrostatic pressure, forcing the dye through the fabric. In this way a very efficient and uniform dyeing effect results.

During the dyeing process the drums and the web of fabric are completely immersed in the bath of dye liquor, the level of which is indicated at line 28. The hydrostatic pressure forces the dye liquor through the entire mass of the web on each drum, passing through the layers in succession. Of course the layers of the fabric on one drum are arranged in reverse order with respect to the layers of fabric on the other drum. While I prefer to carry out the process by forcing the dye liquor through a plurality of layers of the fabric, it is evident that in practising the invention a single web of material could be guided around the drums so that the sides of the material would be exposed on the outside of the drums in succession, in which case the dye liquor would be forced through a single layer of the material in one direction first, and then in the other direction.

It is understood that the embodiment or my invention described above is only one of the many embodiments or forms the invention may take, and I do not wish to be limited in the practice of the invention nor in my claims to the particular embodiment described.

What I claim is:

1. The process of dyeing a fabric, which consists in forming a mass of a plurality of layers of the fabric arranged adjacent to each other, forcing the dye liquor through the said layers in succession in a certain direction, forming a second mass of the same fabric with the same layers arranged in reverse order, and forcing the dye liquor through the last named layers in succession in the same direction as before.

2. The process of dyeing a fabric, which consists in forming a mass of a plurality of layers of the fabric arranged adjacent to each other, forcing the dye liquor through the said layers in succession in a certain direction, forming a second mass of the same fabric with the same layers arranged in reverse order, forcing the dye liquor through the last named layers in succession in the same direction as before, and passing the fabric from one of said masses to the other

while the dye liquor is being forced through said layers.

65

3. The process of dyeing a fabric, which consists in forming an open coil of layers of the fabric, forcing the dye liquor through the said layers in succession in a certain direction, forming a second coil of the same fabric of layers coiled in a reverse direction with respect to said first coil, and forcing the dye liquor through the second named coil in the same direction as before.

76

4. The process of dyeing a fabric, which consists in wrapping the fabric into a coil, forcing a dye liquor through the layers of said coil in succession, wrapping said web into a second coil coiled in a reverse direction with respect to said first coil, forcing the dye liquor through the layers of the second coil in succession so that the direction of movement of the liquor with respect to both coils is the same, and maintaining the coils immersed in a bath of the dye liquor.

80

5. The process of dyeing a fabric, which consists in wrapping the fabric into a coil, forcing a dye liquor through the layers of said coil in succession, wrapping said web into a second coil coiled in a reverse direction with respect to said first coil, forcing the dye liquor through the layers of the second coil in succession so that the direction of movement of the liquor with respect to both coils is the same, maintaining the coils immersed in a bath of the dye liquor, and circulating the dye liquor.

85

6. The process of dyeing a fabric which consists in passing a wound up web of the fabric through a dye bath, subjecting the so wound fabric to hydrostatic pressure in said bath on one side to force the dye liquor therethrough in one direction and winding up said fabric with its layers arranged in reverse order, and thereafter subjecting the other side of the fabric to hydrostatic pressure to force the dye liquor through the fabric in the opposite direction.

90

7. The process of dyeing a fabric which consists in maintaining a bath of dye liquor, forming a mass of a part of a fabric in a plurality of layers arranged adjacent to each other, forming a second mass of another part of the same fabric with the layers also arranged adjacent to each other, both of said masses of fabric being submerged in said bath, and forcing the liquor of said bath through the masses of fabric simultaneously.
